UNITED STATES PATENT OFFICE

CARL J. SCHOBRONE, OF CLEVELAND, OHIO

AIR PURIFIER

Application filed March 2, 1929. Serial No. 343,877.

My invention pertains to an air purifier and more particularly to an apparatus involving some of the operating principles of my Patent No. 1,595,060 of August 3d, 1926, 5 for "Smoke treating apparatus" and of my Patent No. 1,641,995 of September 13, 1927 for "Smoke treating apparatus," though additionally adapted effectively to purify air which has become impregnated with noxious 10 fumes or elements.

Besides the generally recognized smoke nuisance caused by many of our industrial plants, a large percent still pollute the atmosphere with fumes which are objectionable 15 if not actually injurious alike to animal and plant life. A more specific object of my invention has been the design of apparatus which will be effective in operation for the intended purpose while avoiding complication 20 and consequential excessive expense of manufacture.

It is to be realized that the scope of my invention comprehends many equivalent constructions. The showing of the drawings 25 and the particular description are merely a specific exemplification of a plurality of mechanical embodiments and arrangements.

Adverting to the drawings:

Figure 1 is an elevation of an air purifying apparatus embodying my invention.

Figure 2 is a top plan view of Figure 1.

Figure 3 is a somewhat enlarged view of a part of Figure 1 with a primary portion disclosed in longitudinally vertical section.

Figure 4 is a horizontal section on line 4—4 of a portion of Figure 3.

Figure 5 is an end view on line 5—5 of Figures 3 and 4.

Figure 6 is a vertical section on line 6—6 of Figures 3 and 4.

Figure 7 is a vertical section on line 7—7 of Figures 3 and 4.

Figure 8 is a vertical section on line 8—8 of Figures 3 and 4.

Figure 9 is a vertical section on line 9—9 of Figure 3.

Figure 10 is a vertical section on line 10—10 of Figure 3.

Figure 11 is a still further enlarged end detail view showing the manner of mixing

screen attachment and connection with a central shaft.

Figure 12 is a relatively transverse view of Figure 11.

Extending from a foundation 1 are a pair 55 of standards 2 and 3 which support a cylindrical mixing chamber composed of two longitudinal halves 4 and 5 and each having longitudinal bordering flanges secured as exemplified by a series of bolts 6. Circular ends 60 7 and 8 are detachably secured in a similar manner by means of bolts 9.

Just beyond the left end of the mixing chamber is a standard 10, and in spaced relation beyond the opposite end of the mixing chamber are a pair of standards 11. The upper end of the standards 10 is provided with a bearing 12 and the upper ends of the standards 11 are likewise provided with bearings 13 and 14. A shaft 15 is mounted in the bearings 12, 13 and 14 and extends through central openings in the heads 7 and 8 of the chamber. Between the bearings 13 and 14 the shaft carries a drive pulley 16. Surrounding the shaft 15 just inside of the heads 70 7 and 8 are stuffing boxes 17.

Impure air or noxious gaseous elements are to be conducted through a flue 18 which is divided into two branches 19 and 20 in front of the head 7, so that the branches diverge to clear the bearing 12 and communicate with the chamber through openings 21 and 22 in the head 7. Interiorly of the chamber the branches again converge at 23 and 24 respectively to communicate with a central 75 80 85 and flared discharge outlet 25 which surrounds the shaft 15.

A series of screens are adjustably secured in the shaft 15 so as to rotate therewith in predetermined spaced relation. As illustrated in Figure 3 seven screens are disclosed, the four to the left being coarser with about $\frac{1}{8}$ inch mesh and the three to the right with finer $\frac{3}{32}$ inch mesh.

The manner in which the screens are 95 mounted is shown in detail in Figures 11 and 12 and involves the employment of collars 26 slidable along the shaft 15 and each adapted to be fixed in any chosen position by means of a set screw 27. One end of each collar 100

detachably carries an annular disc 28 affixed with circumferentially arranged screws 29 and annular screens 30 are clamped to the disc 28 by means of circumferentially disposed rivets 31.

5 A pipe 32 connects with a source of spraying fluid (water or appropriately impregnated fluid according to requirements) and the supply may be controlled by means of a 10 valve 33, the opposite sides of which is connected with a T 34, one outlet of which is connected by means of a union 35 with a pipe 36 entering the top of the chamber through an opening 37 over the discharge outlet 25. The 15 pipe 36 terminates interiorly of the chamber as a C-shaped nozzle disposed as though turned clockwise through an arc of 90° and provided with perforations 38. The curved nozzle surrounds the discharge outlet 25 except 20 for the dividing space 38a between their lower extremities and is adapted to spray toward the other end of the chamber as illustrated in Figure 3. A union 38b is shown in Figure 3 and is intended to facilitate detachment of the curved nozzle from the piping 25 above it.

The other end of the T 34 communicates by means of a union 39 with another pipe 40 preferably composed of lead and entering 30 the top of the chamber at about its longitudinal middle. The pipe 40 is likewise supplied with perforations 41 and extends across the chamber, being however fashioned at the center thereof with a bend 42 so as to pass 45 halfway around the shaft 15.

It is to be observed in Figure 3 that three screens of the coarser mesh are interposed between the two spray nozzles 38 and 41 and that another single one of the coarser screens 40 30 is disposed close to the opposite side of the nozzle 41. However, instead of permitting the spray from the nozzle 41 to travel freely past all of the interior margin of this particular screen 31, I provide just ahead 45 of that screen an annular baffle 43 provided with a marginal flange 44 which conforms to the interior surface of the cylinder except for a short gap or drain aperture 45 at the bottom, as clearly appears in both Figures 3 and 50 8. The margin of the other face of the baffle 43 (which is of annular cross-section) defines a central opening 46 of somewhat smaller diameter than that of the screens 30. By this arrangement the spray is compelled to pass 55 through the particular screen 30 which is just ahead of the nozzle 41 with reference to its direction of spray toward the end 8 of the cylinder.

50 A plurality of mixing screens 47 (3 as shown) of relatively finer mesh are selectively adjustable in spaced relation between the baffle 43 and the end 8 of the mixing chamber. It is to be understood that the manner 55 of support and adjustable attachment of the

finer screens 47 is the same as described and shown in Figures 11 and 12.

A storage tank 48 is suitably carried adjacent to the mixing chamber and in a relatively elevated position. The tank 48 is to contain a supply of a liquid chemical, selectable according to its intended function of auxiliary purification and it is provided with a valve controlled outlet 49 communicating through a pipe 50 with the top of the mixing chamber within which it is supplied with a discharge nozzle 51 located between two of the screens 47 and bent toward the outlet end of the cylinder.

Beyond that screen 47 which is nearest the end 8 of the mixing chamber the latter is provided with an upper outlet 52 leading to the stack 53. Projecting through the outlet 52 partially into the stack is a suction or draft pipe 54, shown in Figures 3 and 9, which is similarly bent half-way around the shaft 15 at 55 and has its lower end projected through an arcuate baffle 56. The baffle 56 has a closed connection with the end 8 and slopes downwardly in a direction toward the opposite end of the mixing chamber where its free edge is raised a slight distance from the bottom. The baffle 56 covers a drain outlet 57 with which the bottom of the suction or draft pipe 54 registers. The outlet 57 communicates with a tank 58 intended to collect soot, foam or solid material, serving the same purpose as the corresponding tanks in my identified patents whereby only water which is free from sediment will escape 100 through the outlet 59 to the sewer.

The back of each of the seven screens carries a semicircular plate 60, and the plates are alternately arranged, that is, at the top and at the bottom of adjacent screens as appears to view in Figure 3. The object of these plates is to baffle the gases to prevent a direct horizontal passage straight through the purifier thereby assuring a better intermingling of the gases with the water sprays by effecting a more complete absorption of the gases by the water.

I claim:

1. In an air purifier, a mixing chamber, a shaft mounted for rotation therein, a duplex inlet conduit divided at its place of entry to said chamber and unified outside and concentrically around said shaft inside of said chamber and an arcuate sprayer around the unified inner end of said conduit.

2. In an air purifier, a cylindrical mixing chamber, fixed bearings outside of said chamber, a shaft axially mounted in said bearings and extending axially through said chamber, a conduit having a duplex entry to said chamber on opposite sides of said shaft and unified inside of said chamber concentrically around and spaced from said shaft and an annular sprayer enveloping the inner end of said conduit.

3. In an air purifier, a cylindrical mixing chamber, a shaft mounted axially therein, mixing devices on said shaft and a conduit having a duplex entry to said chamber and unified outside, and inside concentrically around said shaft and an annular sprayer enveloping the inner end of said conduit. 70
4. In an air purifier, a chamber provided with an inlet and an outlet, a liquid sprayer 10 interiorly of said chamber near its inlet end, a screen rotatably mounted in said chamber and beyond said sprayer with reference to said inlet, a water spraying pipe extending across said chamber beyond said screen, and 15 a baffle beyond said last mentioned sprayer and provided with a central opening of smaller diameter than the length of said pipe. 80
5. In apparatus of the character described, the combination of a mixing chamber provided with an inlet at its one end and a pair 20 of outlets at its other end, agitating devices within said chamber, and a connection between said pair of outlets and extending across said chamber. 85
6. In apparatus of the character described, the combination of a horizontally elongated mixing chamber provided with an inlet at its one end and a pair of outlets one at the top and one at the bottom of its other end, agitating 25 devices within said chamber, a connection between said pair of outlets and extending across said chamber and a baffle over said bottom outlet and intersected by said connection. 90
7. In apparatus of the character described, the combination of a horizontally disposed cylindrical mixing chamber provided with an inlet at its one end and a pair of outlets at the top and bottom of its other end, a shaft 30 mounted at the axis of said chamber, screens mounted on said shaft, means for supplying a fluid to said chamber, an arcuate baffle over said bottom outlet and a conduit projecting through said baffle and also through said top 45 outlet. 95
8. In apparatus of the character described, the combination of a cylindrical mixing chamber disposed substantially horizontally, a shaft axially mounted in said chamber, a bifurcated conduit entering one end of said chamber on diametrically opposite sides of said shaft and discharging at a common opening intersected by said shaft, a spray nozzle within said chamber and surrounding 50 said single discharge opening, screens mounted upon said shaft and a baffle intermediately of the ends of said chamber and cooperating therewith to close a major segment of the circular plane which it occupies. 100
9. In apparatus of the character described, the combination of a cylindrical mixing chamber disposed substantially horizontally, a shaft axially mounted in said chamber, a bifurcated air conduit entering one end of 55 said chamber on opposite sides of said shaft 105
- and discharging at a common opening intersected by said shaft, fluid spray nozzles at longitudinally spaced points within said chamber, each nozzle extending across said chamber and last said shaft, circular screens 60 adjustably mounted at spaced points upon said shaft and with their annular edges spaced from the wall of said chamber and a segmental baffle intermediately of the ends of said chamber and cooperating therewith to close throughout its extent the passage of mixed air and fluid between the margins of some of said screens and the interior wall of 70 said chamber. 75
10. In apparatus of the character described, the combination of a horizontally elongated mixing chamber, a spraying device therein, rotary screens in spaced longitudinal alinement with said chamber, each of 75 said screens having attached thereto a semi-circular baffle plate, said baffle plates being staggered with respect to each other. 80
11. In an air purifier, a cylindrical mixing chamber composed of two longitudinal halves, a shaft mounted axially thereof, and a C-shaped sprayer enveloping said shaft and attached to one half of said chamber whereby to permit of the passage of said shaft through the gap in said sprayer during the disconnecting of said sprayer-carrying 90 half of the chamber. 95
